CLAIM

The ornamental design for a valve as shown and described.

DESCRIPTION

FIG. 1 is a perspective view of a valve showing my design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is a cross section view showing the valve inside of a
quick coupler as a condition of use.

The broken lines shown in the figures are included for the
purpose of illustrating environment and form no part of the
claimed design.
